UNITED STATES PATENT OFFICE.

LUTHER MERRILL, OF SAN MARTIN, CALIFORNIA.

DESIGN FOR A HAT AND CLOTHES RACK.

49,068.

Specification for Design.

Patented May 16, 1916.

Application filed September 18, 1914. Serial No. 862,416. Term of patent 14 years.

To all whom it may concern:

Be it known that I, LUTHER MERRILL, a citizen of the United States, residing in San Martin, in the county of Santa Clara and State of California, have invented a new, original, and ornamental Design for a Hat and Clothes Rack, of which the following is a specification, reference being had to the accompanying drawing, forming part thereof.

The figure is a perspective view of the hat and clothes rack, showing my new design.

I claim:

The ornamental design for hat and clothes rack, as shown.

LUTHER MERRILL.

Witnesses:

FRANK LAINE RHODES,
PATRICK JOHN BARTLETT.
